UNITED STATES PATENT OFFICE.

CHARLES DUSTIN, OF AVOCA, NEW YORK.

LANTERN-LIGHTER.

1,107,049.

Patented Aug. 11, 1914.

Application filed August 14, 1913. Serial No. 784,749.

To all whom it may concern:

Be it known that I, CHARLES DUSTIN, a citizen of the United States, residing at Avoca, in the county of Steuben and State 5 of New York, have invented new and useful Improvements in Lantern-Lighters, of which the following is a specification.

The primary object of the invention is the provision of simple and effective means, 10 whereby a lantern or analogous form of lamp may be conveniently lighted without requiring the lifting of the globe or the separation of the lamp from the lantern body and to overcome the difficulty a person 15 has in lighting when there is a draft or wind.

The invention provides a match scratching attachment which may be readily fitted to the base of the lantern of standard makes, 20 said match scratcher being of such construction and arrangement as not to interfere with the flange of the base which encircles the lower portion of the globe, thereby obviating the necessity of a special formation of base or 25 globe in order to adapt the invention to lanterns.

The invention consists of a match scratcher having an opening at one end near the globe retaining flange for the introduction 30 of the match when lighted preliminary to applying such match to the wick for lighting the same.

This attachment is fitted to the bottom or side of the base and comprises upper and lower guides and terminal stop, the latter being in position to arrest the movement of the match when lighted so as to direct the match through the opening in the base, this, 40 however, can be used with or without the stop.

The invention consists of the novel features, details of construction and combination of parts, which hereinafter will be more particularly set forth, illustrated in the accompanying drawing, and pointed out in the appended claims.

Referring to the drawing, forming a part of the specification, Figure 1 is a top plan view of a lantern base embodying the invention. Fig. 2 is an edge view thereof. Fig. 3 is a section on the line $x-x$ of Fig. 2. Fig. 4 is a detail perspective view of the preferred form of match scratch. Fig. 5 is a modification. Fig. 6 is a further modification showing the match scratch, forming an

integral part of the base, such match scratch being pressed in the side or rim of the base. Corresponding and like parts are referred to in the following description, and indicated in all the views of the drawing, by the 60 same reference characters.

The numeral 1 designates the base of a lantern which may be of any form commonly provided and embodies a bottom and an upstanding rim or flange, the latter 65 adapted to encircle the lower end of the globe in the manner well understood. An opening 2 is formed in the bottom of the base near the globe retaining rim or flange and provides for the introduction of the 70 lighted match when it is desired to light the lantern. The opening 2 may be of any size or form and is arranged so as not to interfere with the globe when the latter is in place.

The match scratcher is located upon the side or bottom of the base 1 and may be secured or pressed into the latter in any way that is preferable or constructed of a sheet metal blank embodying a rear wall 3 and 80 upper flange 4, a bottom flange 5 and terminal stop 6 which arrests the movement of the match when scratching the same.

The rear wall 3 is roughened to provide an abrasive surface for igniting the match when 85 the latter is moved thereover in contact therewith as mentioned above. The upper flange 4 provides convenient means for securing the match scratcher to the base 1, unless match scratcher is pressed into base 90 as mentioned above. The bottom flange 5 supports the match and insures the same being retained in contact with the rear wall 3. The match scratcher is arranged with the stop 6 in line with one end of the opening 95 2 so as to arrest the movement of the match and insure guiding the same through the opening 2 when lighting the lantern.

The arm 7 if used forms a part of the blank from which the match scratcher is 100 formed and preferably consists of an extension of a bottom flange 5 of which the terminal stop 6 likewise forms a part. The arm 7 also assists materially in holding the match scratcher in place if stop 6 is used. 105 The opening 2 can be arranged between the outer end of the match scratcher and the stop 6, hence is arranged within the end of the match scratcher. The end portion of the upper flange 4, if preferred, may be cut 110

away opposite the opening 2 so as not to obstruct the same and the entrance of the lighted match therethrough.

The rear wall of the match scratcher may 5 be straight, as shown most clearly in Figs. 3 and 4, or it may be of V form as indicated in Fig. 5. In some instances the guide arm 7 may be dispensed with, hence the modification illustrated in Fig. 5 omits such part.

10 From the foregoing description, taken in connection with the accompanying drawing, the advantages of the construction and of the method of operation will be readily apparent to those skilled in the art to which 15 the invention appertains, and while I have described the principle of operation of the invention, together with the device which I now consider to be the best embodiment thereof, I desire to have it understood that 20 the device shown is merely illustrative, and that such changes may be made when desired as are within the scope of the claims appended hereto.

Having thus described the invention what 25 is claimed as new, is:—

1. In a lantern and in combination with the base having an opening near its outer edge, a match scratcher located below the base and to one side of the opening therein

and comprising a rear roughened wall, upper and lower parallel flanges at the longitudinal edges of the rear wall and a guide arm at one end of the rear wall and passing through the opening of the base thence over the top thereof to direct the lighted match 35 to the wick tube.

2. In a lantern and in combination with the base having an opening near its outer edge, a match scratcher located below the 40 base and to one side of the opening therein and comprising a rear roughened wall, upper and lower parallel flanges at the longitudinal edges of the rear wall, a stop at one end of the rear wall and a guide arm in line with the stop and extending through the 45 opening of the lantern base and over the top thereof to direct the lighted match to the wick, the upper flange terminating short of the stop and guide arm so as not to obstruct the passage of the lighted match 50 through the opening of the lantern base.

In testimony whereof I affix my signature in presence of two witnesses.

CHARLES DUSTIN.
